UNITED STATES PATENT OFFICE.

CHARLES E. WINKLER, OF NEW YORK, N. Y.

STILETTO.

Application filed February 15, 1923. Serial No. 619,307.

This invention relates to embroidery instruments, awls or stilettos in general and particularly to a kind which is adjustable.

The prime object of my invention is to provide a handy inexpensive and efficiently working article, which may be readily fitted to the operator's hand, and which is provided with a particularly designed finger rest so as to permit the fingers of the operator to press the device against the cloth which is to be pierced.

Another object of my invention is to make the parts comprising the article smooth and handy and without objectionable obstructions.

Another object of my invention is to provide within such device an adjustable member adapted not only to limit the piercing stroke of the device but at the same time serving as a protection against injury to the operator when carrying the device and when the latter is not in use.

The foregoing and still further objects will be more fully apparent from the following description and the drawings forming part of this specification, and in which:

Figure 1 represents a piercing member.

Figure 2 is the outer sleeve member partially in section.

Figure 3 the inner sleeve member partially in section.

Figure 4 represents an assembly in longitudinal cross-sectional view showing the way it is applied.

Figure 5 is a modified form of a part of the adjustable inner sleeve member.

Figure 6 is a cross sectional view taken on line 6—6 of Figure 4.

Referring to the drawings numeral 10 denotes the piercing or pointed member of the device, which is substantially cylindrical in shape and tapering at one end as indicated at 11 to a sharp point indicated at 12. At the opposite end of the piercing member 45 there is provided a head or knob 13 which is preferably knurled. Adjacent to the head there is provided a reduced threaded portion 14, which is adapted to engage an internally threaded outer sleeve 15 at the latter's 50 upper end.

Sleeve 15 comprises a generally cylindrical member tapering somewhat at its lower portion 16. Adapted to also engage internally threaded outer sleeve 15 at its lower 55 end there is shown in detail in Figure 3 the

inner sleeve 17 provided with a threaded head 18 and a substantially conical enlargement 19 serving as a finger rest when pressure is to be applied with the article against the material to be pierced.

In operation the inner sleeve 17 is set in desired relation to outer sleeve 15 and the pointed member 10. By so doing the device may be set to pierce holes of any desired diameter. It is evident that the adjustment 60 for a larger hole may be made by screwing the inner sleeve into the outer sleeve, thereby increasing the distance between point 12 and the face 19' of enlargement 19. By working sleeve 17 in an opposite direction the hole 70 capable of being made by the piercing member will be smaller.

When sleeve 17 is brought out further until threaded head 18 becomes flush with the edge of the lower tapered end 16 of outer sleeve 15, pointed end 12 of piercing member 10 will be in alignment with the face 19' of the enlargement 19 of the outer sleeve. In this position the article may be carried in a pocket without injury to the bearer.

While I have shown in the drawing a particular form of my device comprising comparatively large elements, be it understood that the same objects and the same advantages may be attained by making the article 85 from very thin tubing as suggested in Figure 5, where the head 119 of outer sleeve member 17' is shown to be made of a hollow form and is provided with an aperture 20 through which the pointed member 10 may 90 be passed.

Similarly the pointed member 10 and sleeve member 15 may be drawn from tubing material.

It is obvious that only the pin portion of 95 the pointed member is to be made sufficiently strong to resist the wear and tear to which it is subjected while the remaining parts may be made of any suitable tubular material and provided with means for adjusting the parts relative to each other, as desired.

While I have shown a specific form of my device, be it understood that changes or improvements may be made within the 100 scope of my invention, for which I claim:

A new article of manufacture, comprising a central pointed member having a knob at one end and a threaded portion adjacent to said knob, an outer sleeve member threaded 110

internally and engaging at one of its ends the threaded portion of said central member, an inner sleeve member having a threaded portion at one end and an enlargement 5 for a finger rest at the other end, the inner sleeve member engaging said outer sleeve member and adapted to be adjusted relative

to said outer sleeve and relative to said central member.

Signed at New York, in the county of 10 New York, and State of New York, this 13th day of February, A. D. 1923.

CHARLES E. WINKLER.
